GEORGE E. CHRISTENSON, JR., OF NORTH PLAINFIELD, NEW JERSEY, ASSIGNOR TO
JOHNS-MANVILLE CORPORATION, OF NEW YORK, N. Y., A CORPORATION OF NEW
YORK

COMPOSITE ARTICLE

Application filed July 9, 1927. Serial No. 204,565.

This invention relates to composite articles formed of rubber and metal, or analogous materials, and more particularly relates to the provision of more satisfactory means for binding the materials together.

The invention is particularly advantageous when applied to swab cups or packing cups for oil wells, which ordinarily comprise outer somewhat yieldable parts of rubber composition secured to inner metal sleeves which are mounted upon the plungers of lifting pumps. By reason of the inevitable roughness and mechanical imperfections encountered in the oil pipes in common use in oil wells, the packings of plungers of this character must encounter unusual strain, and therefore are desirably of very sturdy construction. Considerable difficulty has previously been encountered in the tendency of the rubber cup to tear away from the metal ring under actual service conditions, while in the manufacture of these swab cups, the separation of the metal ring and the composition packing has frequently occurred when the cup was being removed from the forming mold.

Heretofore it has been common to form external threads or grooves in the metal ring and to vulcanize the composition packing directly in place with portions of the packing embedded in the grooves. The present invention affords a more effective union between the metal ring and the rubber packing by providing an intermediate layer of agglutinous material having circumferentially arranged strands, which are adapted to be located within the grooves. In its more specific aspect, this invention therefore relates to the provision of rubberized fabric which is firmly stretched around and secured to the threaded or grooved face of the metal ring, and to the vulcanization of the cup in place upon the outside of this fabric, the strands of the fabric providing means for more firmly retaining the cup in place upon the ring.

In the drawings which illustrate my improvements,

Fig. 1 is a view of a swab cup constructed in accordance with my invention, the cup

being shown half in elevation and half in transverse section;

Fig. 2 is a plan view of the metal ring and the fabric applied thereto before the composition packing is secured to the outer face of the fabric; and Fig. 3 is an enlarged section on line 3—3 of Fig. 1.

A lifting cup such as is commonly used in removing petroleum products from oil wells may comprise a rubber composition portion in the form of an outwardly flaring member provided with suitable slots in order to receive metal reinforcements or the like. For example, Fig. 1 shows such a composition packing member designated by the numeral 1 and provided with the slots 12. In use a swab cup of this character is mounted upon a central plunger or swab head and a suitable metal ring 2 is provided to engage this plunger.

The present invention discloses an improved means for securing the cup 1 to ring 2. For this purpose the exterior surface of the ring is threaded or grooved, as designated by the numeral 3. Thereupon one or more layers of rubberized fabric are stretched about the periphery of the ring 2, such fabric being designated by numeral 4 and being provided with overlapping skived portions 6, which may be firmly secured to each other during the manufacture of the cup. It will be evident from an inspection of Fig. 3 that the rubberized fabric is arranged with strands running in the same general direction as the threads or grooves 3, it being evident that the yieldable nature of the fabric permits close interfitting engagement of its inner face with the grooves upon the outer portion of the ring; while its outer face reproduces the grooves 3 in less exact form, as designated by numeral 5. The unvulcanized rubber which is to form the cup 1 may be pressed into the corrugations 5 and the cup and rubberized fabric may then be compressed and vulcanized in a suitable mold while the overlapping fabric portions are firmly held in place. The cup 1 is thus firmly welded to the fabric, while the latter is maintained in interlocking engagement with the grooves 3.

The resulting composite article formed of rubber composition and metal is of unusually sturdy construction, due to the interlocking of the rubberized fabric with the metal cup 5 and the composition packing and due to the vulcanization of the overlapping fabric ends to each other as well as to the packing. A joint of this character between the rubber composition cup 1 and the threaded exterior 10 of the ring 2 has been found to be much more firm and sturdy than the type of unions previously provided in this art.

I claim:

1. An article of the class described comprising a tubular member of material having the properties of a rubber composition, a circumferentially grooved ring, and strands impregnated in similar material and disposed in the grooves of the ring, the ring with the 15 strands thereon providing an uneven peripheral surface, said member being vulcanized upon the uneven surface thus formed.
2. An article of the class described comprising a tubular member of material having the properties of a rubber composition, a circumferentially grooved ring, and rubberized fabric wound about the grooved portion of the ring with its face pressed into interfitting engagement with the grooves thereon, and 20 with strands running generally in the direction of said grooves, the outer face of said wound fabric being uneven to conform to the grooved periphery of the ring, said tubular member being vulcanized to said outer face.
3. An article of the class described comprising a tubular member of material having the properties of a rubber composition, a grooved ring, and rubberized fabric wound about the grooved portion of the ring with 25 its face pressed into interfitting engagement with the grooves thereon, the outer face of said fabric being provided with less sharply defined grooves reproducing the grooves upon the ring, said member being vulcanized 30 to said grooves upon the outer face of the fabric.
4. An article of the class described, comprising a metal member having a threaded portion, a member of rubber composition and 35 means securing the composition member to the metal member comprising a rubberized fabric wound about the threaded portion of the metal member and vulcanized thereon and to the rubber composition member, said fabric 40 having overlapping portions vulcanized in place, and having an irregular outer face conforming with the threads upon the ring, said rubber composition member being 45 pressed into engagement with said outer face and vulcanized thereto.
5. An article of the class described comprising a metal ring, a packing cup of rubber composition disposed about the ring, substantially circumferential grooves upon the 50 periphery of the ring, rubber-impregnated fab-

ric stretched about the ring and interfitting with the grooves thereon, portions of said fabric being skived and adhesively held in overlapping engagement, said portions being vulcanized to each other, said fabric being 55 vulcanized upon the grooves and having an uneven outer face conforming with the general contour of the grooved portion of the ring, said composition cup being pressed and vulcanized in engagement with said uneven outer face.

Signed by me at Manville, New Jersey, this seventh day of July, 1927.
